UNITED STATES PATENT OFFICE.

FORD W. HARRIS, OF LOS ANGELES, CALIFORNIA.

FILE FOR SOUND-REPRODUCING RECORDS.

1,186,478.

Specification of Letters Patent.

Patented June 6, 1916.

Continuation of application Serial No. 693,836, filed April 29, 1912. This application filed September 1, 1915.
Serial No. 48,548.

To all whom it may concern:

Be it known that I, FORD W. HARRIS, a citizen of the United States, residing at Los Angeles, in the county of Los Angeles, State 5 of California, have invented a new and useful File for Sound-Reproducing Records, of which the following is a specification.

My invention relates to the article filing art. In that art primary records are produced by a suitable recorder. These primary records, or secondary records made from them, when used with a suitable reproducer will reproduce to a certain degree the original sounds. The majority of the 10 phonographs now in use employ a flat disk record from one-eighth to five-sixteenths of an inch in thickness, the records being made of molded or cast material and being made commercially in several diameters, twelve 15 inches and ten inches being the most usual sizes. Such records have the reproducing marking indented in spiral grooves on one or both sides of the record. The owner of a phonograph often gets a large collection 20 of these records, and some convenient means for preserving them, so that they are quickly available, is quite essential.

The principal object of my invention is to provide novel means for filing and preserving such disk records. Various methods of filing have already been devised. For example, paper envelopes may be used into which the records are slipped. These envelopes may then be bound together at one 25 edge into a book and a sufficient number of books may be provided to take care of any desired assortment of records. Such books are objectionable in that they are somewhat expensive and difficult to handle, and in that 30 different sizes of books must be provided for different diameters of records. They are also objectionable in that they are heavy and cumbersome, do not admit of ready indexing, and in that they take up an undue 35 amount of space. For the purpose of overcoming these disadvantages and objections, I have devised the filing means illustrated in the accompanying drawings.

My invention comprises the following 40 novel features: (A) Individual envelopes for each record, these envelopes being supported solely by an upper edge and being open at a forward edge to permit of the easy insertion and removal of records. (B) Supporting means for each envelop which will

permit it to hang normally in the back of a cabinet or permit it to be drawn to a forward position so that the record can be easily removed. (C) A new form of tab for each envelop by which the contents may 45 be identified. (D) Closure means for the front edge of the envelop so arranged as to exclude dust from the interior of the envelop. (E) Reinforcing means in the top of the envelop on which the envelop slides. 50

Of the above structural features it is to be noted that features (A) and (B), as well as certain other novel and useful features are disclosed in my application, Serial No. 693,836, filed April 29, 1912, of which this 55 application is a continuation.

In the drawings, which are for illustrative purposes only: Figure 1 is a perspective view of a filing cabinet equipped with my invention. Fig. 2 is a vertical central section through the center of such a filing cabinet showing a record in place therein. Fig. 3 is an enlarged view of one of the envelops used in my invention with its supporting rod, a portion thereof being broken away 60 to better illustrate the invention, and a record being shown in place therein. Fig. 4 is a section on a plane represented by the line x^4-x^4 in Fig. 3. Fig. 5 is a partial section on a plane represented by the line 65 x^5-x^5 in Fig. 3, looking in the direction of the arrows. Fig. 6 is a sectional view of an alternate form of my invention. Fig. 7 is a partial section on the line x^7-x^7 of Fig. 6 looking in the direction of the arrows. 70 Fig. 8 is a view of another alternate form of construction of my invention. Fig. 9 is a view of a novel form of spacing strip. Fig. 10 shows an alternate form of rod used in my invention. Fig. 11 is a perspective 75 view of a cabinet showing the method of taking hold of the individual envelops. Fig. 12 is a view showing an individual envelop withdrawn to the front of the cabinet. Fig. 13 is a view showing the accessibility of the record when the envelop is so withdrawn. 80

The principal feature of my invention is the form of envelop which is used to contain the record, in combination with the suspension means for the same. 85

Previous inventors have used flexible or semi-flexible envelopes either bound in books supported at the bottom, or sliding in compartments. So far as I am aware I am the 90 110

first inventor to use a flexible envelop which is supported wholly from the top.

The preferred form of envelop is illustrated in Fig. 3. The envelop 20 is open along a front edge 21, being closed along the bottom edge 22, the back edge 23 and the top edge 24. An opening 25 is formed at the intersection of the edges 23 and 24, and a supporting rod 26 is passed through the envelop, projecting through the front edge 21 and through the opening 25. A rigid reinforcing member 27, which may be formed of wood in semi-circular form, as shown in Fig. 5, or which may be of canvas, or metal, if desired, is placed inside the top edge 24 above the rod 26. The forward edges 21 may be left plain, or they may preferably be reinforced as shown in the drawing. In either case, a tab 30 is secured to one side of the envelop at the front edge 21. This tab is preferably secured as shown in Fig. 4, in which the sides 31 and 32 of the envelop are bent over as shown at 34 and 35. The tab 30 has projecting ends 36 and an index portion 37. The index portion 37 fits inside of an opening 38 formed in the bend between the side 32 and the member 34. The projecting ends 36 prevent the tab 30 from being pulled through the opening 38. For the purpose of forming a tight closure in the front edge 21 of the envelop, plush members 39 may be used, these members being glued or cemented to the folds 34 and 35. These plush members 39 not only serve to make a dust proof enclosure of the front of the envelop, but they also provide a ready means for brushing any dust from the record as it is inserted in the envelop. The tabs 30 are preferably bent at a slight angle, as shown in Fig. 4, so that they will be more readily visible from the front of the cabinet when properly assembled. The tabs 30 are arranged successively on successive envelops, as shown in Fig. 1, and they are successively numbered as shown at 40, these numbers being visible due to the arrangement of the successive tabs, as illustrated in Fig. 1. The envelops 20 may be readily restrained on the rods 26 so that they cannot slide thereon, and my invention includes any such arrangement. I prefer, however, to arrange the envelops to slide longitudinally of the rods 26.

The envelops are preferably arranged side by side in a cabinet such as that illustrated in Fig. 1, the rods being supported in a number of ways. In the method illustrated in Fig. 2, the cabinet consists of a top 41 having a back 42 and a pair of hinged doors 43 and 44. Supporting strips 45 and 46 extend across the front, and a shelf 47 extends across the cabinet above the strip 46. Supporting members 48 are secured to the strips 45 and 46 and to the

back 42, and perforated metal plates 49 are secured thereto by means of screws 50. These perforated metal plates 49 are illustrated in detail in Fig. 9. In this form of my invention the rods 26 project through small openings 51 punched in the plates 49, these plates serving to support the rods 26 and to prevent them from moving sidewise, so that there is no danger of crowding the envelops 20 to one end or the other of the cabinet. The rods 26 are made of sufficient length to allow the envelops 20 to be pulled forward into the position shown in dotted lines at 52 in Fig. 2. Alternate methods of supporting the rods 26 are illustrated in Figs. 6 and 8. In Fig. 6 supporting members 53 are secured to the member 45 and to the back 42 respectively. A series of small brads 54 are driven upwardly through the strips 53, so that the rods 26 are spaced thereby in their proper relationship and are thereby prevented from moving sidewise. In Fig. 8 the strip 45 and the back 42 have holes 56 and 57 drilled therein through which the rods 26 pass and into which they fit. The holes 57 are closed by a plate 58. If desired the strips 53 illustrated in Fig. 6 may be used without the brads 54, in which case the rods 26 are provided with thimbles 58, these thimbles 58 being larger in diameter than the rods 26 and serving to space them apart. When so constructed, the envelops are allowed to have a slight sidewise motion, the thimbles 58 sliding longitudinally of the strips 53.

In the forms of my invention illustrated in Figs. 2 and 6, the corner of the envelop is cut off diagonally about the opening 25 so that the back 23 of the envelop 20 can strike against the back 42 of the cabinet when the envelop is pushed to its extreme rear position. In the form of the invention illustrated in Fig. 8, it is not necessary to so cut the envelop, as it is not necessary to make any projection from the back 42 of the cabinet. The strips 53 and the plates 49 being located at the front of the cabinet serve as a limiting stop against which the envelops may be pulled forward into the position shown by dotted lines at 52 in Fig. 2. The envelops can also be slid back on the rods 26 until they strike on the back 42 of the cabinet.

While I have illustrated in Fig. 1 a preferred form of cabinet having an upper and a lower compartment, it is obvious that my particular form of filing envelop and suspension means therefor can be used in any desired form of cabinet and with any desired number of envelops.

The method of operation of the invention is illustrated in Figs. 11, 12, and 13. The envelops being consecutively numbered, a card or book index is maintained showing in which particular numbered envelop the

desired record is held. While I prefer to file each record in its individual envelop, it is of course obvious that where a cheap cabinet is required more than one record can be filed in an envelop if desired. The user of the cabinet having determined from his index the number of the envelop containing the desired record, he proceeds to draw the envelop forward by seizing the numbered tab as shown in Fig. 11 and drawing it to its extreme forward position, as illustrated in Fig. 12. The envelop then being well advanced from its fellows, it is possible for him to insert his hand into the envelop, as shown in Fig. 13, and to withdraw the record therefrom. Figs. 11, 12 and 13 are made from actual photographs. It is, of course, not necessary to insert the hand as far as is shown in Fig. 13 unless it is desired to do so, it being possible to catch the record between the thumb and fingers. The record is then drawn forward out of the envelop, the envelop remaining stationary in the front of the cabinet as shown in dotted lines at 52 in Fig. 2, and as shown in Figs. 12 and 13. As soon as the user has finished playing the particular record, he slips it back into the envelop, the tab 30 serving as a guide to direct the edge of the record into the space between the sides 31 and 32. As the record slides into the envelop the cloth members 39 brush any dust which may have accumulated from the surface of the record, the record sliding back into the position shown in Fig. 3. In Fig. 3 the largest size of commercial record is shown in place in the standard envelop. The length of the envelop is sufficient to allow the record to pass entirely by the plush members 39 so that they can close, thus excluding any dust from the interior of the envelop and record.

The envelop 20 may be made of comparatively light and tough paper, as the weight of the record tends to hold the sides straight.

While I have illustrated in Fig. 3 an envelop containing the largest size of commercial record, it is possible to file therein records of such smaller diameter, as shown by the dotted lines 60 of Fig. 3. In practice the twelve inch record is at present the largest commercial size. Ten inch records, indicated approximately by the dotted lines 55 60 of Fig. 3, are quite common, and six inch records, as indicated by the dotted lines 61 of Fig. 3, are also coming into general use. Any of these three sizes can be filed in any envelop, and it makes no difference whether these envelops are of the least commercial thickness, or whether they are five-sixteenths of an inch in thickness, this being the thickness of the Edison disk record, which is the heaviest make being shown in commercial quantities,

It is extremely common for the user of a phonograph to have quite a large number of records of a single production, such as an opera, and it is desirable that these records all be filed together. It very often happens that they are of different diameters and thicknesses, and it is obvious that were the envelops not suited to any size of record that it would be impossible to accomplish this. By the use of my cabinet the greatest space economy is attained, as the records hang side by side, separated only by two thin thicknesses of paper. All the other advantages mentioned in the preamble of the specification are also attained, as will be readily understood from the foregoing description.

While I have illustrated and shown certain preferred embodiments of my invention, I do not wish to be understood as limiting myself to these particular embodiments, and I desire that the scope and limitations of my invention be governed wholly by the annexed claims.

I claim as my invention:—

1. A filing cabinet for flat circular phonograph records comprising a supporting structure, a series of envelops each of sufficient size to contain at least one of said records, each of said envelops having an opening in a vertical edge through which a record can be inserted or removed, and a supporting rod for each of said envelops on which each of said envelops is hung, each of said rods being supported by said structure. 95

2. A filing cabinet for flat circular phonograph records comprising a supporting structure, a series of envelops each of sufficient size to contain at least one of said records, each of said envelops having an opening in a vertical edge through which a record can be inserted or removed, and a supporting rod for each of said envelops on which each of said envelops is hung, each of said rods being supported by said structure, and each of said envelops being free to slide longitudinally on its supporting rod. 105

3. A filing cabinet for flat circular phonograph records comprising a supporting structure, a series of envelops each of sufficient size to contain at least one of said records, each of said envelops having an opening in a vertical edge through which a record can be inserted or removed, and a supporting rod for each of said envelops on which each of said envelops is hung, each of said rods being so secured to said supporting structure that said rod cannot move with relation to the structure. 115

4. In a filing cabinet having a plurality of suspended envelops, a supporting means for each envelop comprising a rod adapted to be slipped through the top of the envelop, and spacing means for holding the rods apart. 125

5. A filing cabinet comprising a supporting structure, a series of envelopes each having an open vertical edge, and a series of supporting members supported in said structure, each of said envelopes being supported by one of said members. 20
6. A filing cabinet comprising a supporting structure, a series of envelopes each having an open vertical edge, and a series of 10 supporting rods supported in said structure, each of said envelopes being supported by one of said rods.
7. A filing cabinet comprising a supporting structure, a series of envelopes each having an open vertical edge, and a series of 15 supporting members supported in said structure, each of said envelopes being supported by one of said members and being free to slide thereon.
8. A filing cabinet comprising a supporting structure, a series of envelopes each having an open vertical edge, and a series of supporting members supported in said structure, each of said envelopes being supported by one of said members and being 25 free to slide thereon, each of said members being rigidly fixed in said structure.
9. A filing cabinet comprising a supporting structure, a series of envelopes, each having an open vertical edge, and means for 30 hanging each of said envelopes in said structure in such a manner that each envelop can slide in its own plane in the structure.

In testimony whereof, I have hereunto set my hand at Los Angeles, California, this 25 35 day of August, 1915.

FORD W. HARRIS.
